UNITED STATES PATENT OFFICE.

SAMUEL J. B. WHITED, OF SHREVEPORT, LOUISIANA.

SIGNBOARD.

Application filed August 8, 1922. Serial No. 580,473.

To all whom it may concern:

Be it known that I, SAMUEL J. B. WHITED, a citizen of the United States, and a resident of Shreveport, in the parish of Caddo and State of Louisiana, have invented certain new and useful Improvements in Signboards, of which the following is a specification.

This invention relates to a sign board. 10 More particularly the present invention relates to the structure of a knock-down sign or bill board and has for its object to provide a structure of this character which may be compactly stored and expeditiously 15 assembled and erected.

A further object of the invention is that the structure when assembled and erected be exceedingly durable and strong.

Other objects, and objects relating to details of construction will hereinafter appear in the detailed description to follow.

The invention is illustrated by way of example in the accompanying drawings, in which:—

25 Figure 1 is a view in rear perspective of the board when erected.

Figure 2 is a vertical sectional view of the same with parts broken away.

Figure 3 is an enlarged view in rear elevation of an end section of the sign board assembled.

Figures 4, 5 and 6 are detail views illustrating the manner in which the structural elements are tied together.

35 Figure 7 is a detail view illustrating the manner in which the sign board may be anchored when erected.

Referring to the drawings more particularly, the sign board may consist in a rectangular frame comprising the two angle end members 10, and the top and bottom angle members 11. The end members are secured to the top and bottom members by the gusset plates 12 and bolts 13. The top and bottom frame members 11 are secured together by a plurality of cross members 14 which are also preferably of angle iron and three in number. The cross members 14 are of sufficient length to extend beneath the bottom frame member 11 and to provide the legs 15. Three concrete wood or angle iron posts P may be positioned in the ground at the place the bill board is to be erected, and each post is provided with a cap 16 which 55 may have extending upwardly therefrom a

post 17 in the form of an angle iron, and this in turn may be secured to the leg portion 15 of the associated member 14. To each member 14 there may also be secured an anchor member 18 which may consist in 60 angle iron, as shown, and be secured at its one end to the member 14 as at 19, while its other end may be secured to an anchor bar 20 which may be embedded in the earth and provided with a cross head 21 to prevent 65 dislodging of the same. The anchor bar 20 may be secured to the member 18 by bolts as at 22. Also suitable braces 23 may be extended between each member 18 and 14.

The intermediate member 14 is preferably 70 secured to the frame members 11 by gusset plates 23' which are preferably of the shape shown. These gusset plates should be secured by the means of bolts so that they may be freely removable.

75 There is also provided a central longitudinal angle frame member generally designated by the reference numeral 24 which is secured at its ends to the end members 10 by the means of bolts as shown in Figure 3. 80 This member is also properly secured by bolts to the members 14 and thus supporting the member 24 in a rigid manner. The construction heretofore described comprises the frame work of the sign board, and all members constituting this frame may be easily taken apart and assembled into a compact 85 unit and also they may be quickly assembled and erected.

Upon the outer portion of each frame 90 member 11 there is secured a strip 26 which is preferably of wood, said strip 26 being secured by the means of bolts 27. Also a similar strip 28 is secured upon the end frame members 10 by means of bolts or the like. 95

A plurality of frames or panels F are provided upon which galvanized sheeting S may be supported, the galvanized sheeting S forming the surface of the bill board upon which the advertising matter may be printed 100 or painted. Also paper may be used to imprint the advertising matter upon and this may be glued or pasted to the sheeting S in the usual manner. Each frame or panel F consists in two vertical members 29, the 105 upper and lower cross members 30 and the intermediate cross member 31. The intermediate cross member is of greater width than the end cross members 30. The end cross members are secured to the vertical 110

cross members by plates 32 and screws or bolts 33. The intermediate cross members 31 are secured to the vertical members 29 by the means of plates as at 34. Also these 5 plates may be employed for securing together the different panels as illustrated. Suitable screws or nails may be employed for securing the plates 34.

The panels or frame members F are in 10 turn secured to the intermediate angle frame member 24 by strips 35, said strips being shown in detail in Figure 6 of the drawings and may be made of galvanized iron or any other suitable metal. The strips 15 should be bent to provide the U-shaped central portion 36 adapted to fit upon the horizontal section or portion of the angle frame member 24 as illustrated in Figure 6, and the ends of the strips may be secured to the 20 longitudinal edges of the frame members 31 by nails or screws as at 37, Figure 6.

It is also to be noted that the frame member 24 is secured to each of the angle frame members 14 by the means of a strap 38, said 25 strap being specifically shown in Figure 5 and consisting in a central U-shaped portion 39 adapted to fit upon the outwardly extending portion 40 of the angle frame member 14. This portion may be secured to the angle 30 frame member by a bolt 41, and the end portions of the strap may in turn be secured to the angle frame member 24 by bolts 42. The end portions of the strap 38 are preferably in the shape of an angle iron as illustrated 35 to advantage in Figure 5.

It should be here stated that the angle bars 24 have their horizontal portions recessed in order to permit the angle bars 14 to cross the same as shown.

40 The sheeting S is held against the frames or panels F by the top and bottom molding boards generally indicated by the reference character 42 as best shown in Figure 2 of the drawings. These molding boards are in 45 each instance, secured to the frame members 11 by bolts 43. These bolts may also extend through the frame members 14, and between the molding boards 42 and angle frame members 11, the top and bottom portions of 50 the panels F are clamped as illustrated in Figure 2, thus insuring that the frame members are rigidly held. The molding boards 42 may have a slight offset 50 occurring upon their inner faces whereby to accommodate 55 a portion of the sheeting S. the sheeting S is preferably made of galvanized iron in order that it may resist rusting. Each end frame member 10 carries a strip as illustrated in dotted lines in Figure 3 and 60 generally designated by the reference character 52. These strips may be secured to the angle frame members 10 by bolts as at 53, and the meeting ends of the strips 42 and 52 might be beveled in order to produce a neat 65 appearance.

If desired a smaller sign board 54 may be supported by vertical members 55 properly secured to the panels F.

It is believed from the foregoing description that the many advantages arising from the present invention may be clearly understood without further reference thereto. It is well to be here pointed out that throughout the entire structure of the board, material is employed which will resist rust and thus to make the sign board last a long period. Also by bracing the sign board in the manner disclosed all danger of the same being blown over in a storm is eliminated.

I claim:—

1. A knock-down sign board, comprising a plurality of vertical members, a post for each vertical member, an anchor bar for each vertical member, a frame supported by said vertical members, a plurality of panels supported within said frame, a sheeting for covering said panels, a molding strip extending about the perimeter of the frame, and means whereby the molding strip may serve to secure the panels in position and also 90 the sheeting.

2. A knock-down sign board, comprising a frame, the side members of which consist in angle iron, a plurality of panels each of which is adapted to extend between said side frame members, a sheeting covering said panels, a molding strip upon the inner side of each frame member, said molding strip being fitted upon the associated portions of the panels and the sheeting, and means for securing the molding strips in position whereby to bind the panels and sheeting to the frame.

3. A knock-down sign board, comprising a frame, the side members of which consist in angle iron, a plurality of panels each of which is adapted to extend between the side frame members, a sheeting covering said panels, a molding strip upon the inner side of each frame member, said molding strip being fitted upon the associated end portions of the panels and the sheeting, and bolts for detachably securing the molding strips to the frame whereby to bind the panels and sheeting to the frame.

4. A knock-down sign board, comprising a frame consisting in two side members and two end members, a brace member extending between the end members, a plurality of panels adapted to extend between the side frame members, each panel having a cross member registering with the brace member, means for securing the panels to the brace member, a sheeting covering the panels, and molding strips extending about the inner 120 perimeter of the frame and adapted for holding the sheeting in position.

5. A knock-down sign board, comprising a frame consisting in two side members and two end members, means for detachably se- 130

curing the side members and end members together, a brace member extending between the end members and secured thereto, a plurality of panels adapted to extend between 5 the side frame members and each panel having a cross member registering with the brace member, straps for securing the cross members of each panel to the brace member, a sheeting covering the panels, and molding 10 strips extending about the inner perimeter of the frame and adapted for holding the sheeting in position.

6. A knock-down sign board, comprising a frame consisting in two side members and 15 two end members, means for detachably securing the side members and end members together, a brace member extending between the end members and secured thereto, a plurality of panels adapted to extend between 20 the side frame members and each panel having a cross member registering with the brace member, straps for securing the cross members of each panel to the brace mem-

ber, a sheeting covering the panels, a molding strip extending about the inner perimeter of the frame and disposed upon the edges of the sheeting, and means for detachably securing the molding strip to the frame whereby to hold the sheeting in position.

7. A knock-down sign board, comprising a 30 frame consisting in two side members and two end members, means for detachably securing the side members and end members together, a brace member extending between the end members and secured thereto, a plurality of panels adapted to extend between the side frame members and each panel having a cross member registering with the brace member, straps for securing the cross members of each panel to the brace mem- 35 ber, a sheeting covering the panels, a molding strip extending about the inner perimeter of said frame and adapted to overlap the sheeting, and means for detachably securing the molding strip to the frame.

SAMUEL J. B. WHITED.
